UNITED STATES PATENT OFFICE

JOHN M. GILL, OF HUNTINGTON, INDIANA.

DESIGN FOR A MILK-STRAINER.

SPECIFICATION forming part of Design No. 15,651, dated December 30, 1884.

Application filed October 14, 1884. Term of patent 14 years.

To all whom it may concern:

Be it known that I, JOHN M. GILL, of Huntington, in the county of Huntington and State of Indiana, have invented and produced a new and original Design for a Milk-Strainer, of which the following is a description.

My design for a milk-strainer consists in a body of inverted-truncated-cone form, ornamented at its lower truncated end with radial side arms or wings, the whole presenting the appearance of a funnel with separated out-stretched arms at its lower end, as hereinafter described and claimed.

The drawing represents a perspective view of a milk-strainer embodying my design.

A indicates the body of the strainer, of an inverted truncated form, and having its lower truncated end relieved from presenting an abrupt appearance and the monotony and same-

ness of its tapering circular configuration broken by three equidistant or triangularly disposed outer side arms or wings, B B B, at right angles, or thereabout, to the axial line of the conical-shaped body, and each of a straight or flattened configuration, forming obtuse angles with one another and lying in the same horizontal plane, as shown.

I claim—

The within-described design for a milk-strainer, which consists in a body of inverted-truncated-cone form, ornamented at its lower truncated end with outwardly-stretched and separated side arms or wings, as shown.

JOHN M. GILL.
